UNITED STATES PATENT OFFICE.

DEMPSEY P. PARKER, OF OSSTEN, FLORIDA.

RAIL-JOINT.

1,392,790.

Specification of Letters Patent.

Patented Oct. 4, 1921.

Application filed April 20, 1920. Serial No. 375,320.

To all whom it may concern:

Be it known that I, DEMPSEY P. PARKER, a citizen of the United States, residing at Osteen, in the county of Volusia and State 5 of Florida, have invented certain new and useful Improvements in Rail-Joints; and I do hereby declare the following to be a full, clear, and exact description of the invention, such as will enable others skilled in the art 10 to which it appertains to make and use the same.

This invention relates to rail joints, and the primary object of the invention is to provide a relatively simple form of joint 15 whereby the meeting ends of the track rails may be placed in an interlocking or co-operative position, and which joint is constructed to be exceedingly strong, to eliminate the use of fish plates, and to so construct the rail 20 joint as to allow for the expansion or contraction of the rails, under different weather conditions, without buckling the rails, or without spreading the rails to such an extent as to render the passage of a train there- 25 over dangerous.

More specifically, an object of the invention is to improve the rail joint disclosed in my Letters Patent #1,203,396, issued October 31st, 1916, by providing a three piece 30 joint, to allow for the expansion and contraction of the rails, which joint comprises a coupling or connecting member which has a longitudinally extending dove-tail formed along one side of the same, that seats in a 35 dove-tail recess carried by one rail of a track, and an inclined substantially vertically extending dove-tail projection and an elliptical projection which fit in corresponding recesses formed in an angled extension 40 formed upon the complementary rail of the track structure.

With the foregoing and other objects in view, this invention consists in such novel features of construction, combination and 45 arrangement of parts as will be hereinafter more fully described, illustrated in the accompanying drawings and claimed.

In describing the invention in detail, reference will be had to the accompanying 50 drawings wherein like characters designate like and corresponding parts throughout the several views, and in which:

Figure 1 is a top plan view of the improved rail joint,

Fig. 2 is a side elevation of the rail joint, 55 having parts broken away, and

Fig. 3 is a vertical section through the rail joint, taken on the line 3—3 of Fig. 2.

Referring more particularly to the drawings, 1 and 2 designate the rails of the track, 60 which are connected by the improved joint structure, and 3 indicates the coupling member employed for connecting the rails 1 and 2. The coupling member 3 has a longitudinally extending dove-tail projection 4 65 formed upon one side of the same, substantially equidistant of the top and bottom surfaces, which dove-tail projection is seated in a dove-tail recess 5 formed in the inner surface of the rail 2.

The rail 1 has an angularly disposed projection 6 formed integrally with the end which meets the end of the rail 2, and disposed laterally therefrom. The major portion of the projection 6 extends parallel to 75 the rail 1 and this projection is provided with a dove-tail recess 7 which extends downwardly at an oblique angle to the perpendicular, as clearly shown in Fig. 2 of the drawings. The projection 6 also has an 80 elliptical recess 8 formed therein, and extending downwardly substantially parallel to the dove-tail recess 7. Both of the recesses 7 and 8 have their constricted openings communicating with the surface of the 85 extension 6 which faces the dove-tail surface of the rail 2, and they receive extensions 9 and 10 respectively, which are formed upon the sides of the coupling member 3, 90 opposite to the side which carries the dove-tail projection 4. The shoulder 12 formed on the end of the rail 1 is cut at an angle, substantially parallel to the recesses 7 and 8 and the shoulder 13 formed upon the transversely extending portion of the projection 95 6 is also cut parallel to the shoulder 12. The ends of the rail 2 and the coupling 3 which fit against the shoulders 12 and 13 are cut and inclined to snugly fit against these inclined shoulders.

The extension 6, coupling 3 and rail 2, are provided with an elongated opening 14 extending transversely therethrough substantially equidistant of their ends which is provided for receiving a bolt 15. The 105 bolt 15 is provided for reinforcing the connection of the members, through the medium of the dove-tails 4 and 9 and the ellip-

tical projection 10, and the elongated opening 14 permits of limited endwise movement of any one of either of the rails 1 and 2 with respect to each other or with respect to the 5 coupling 3, to compensate for the expansion or contraction of the rails under weather conditions.

To connect the meeting ends of the rails 1 and 2, the coupling member 3 is first connected to the extension 6, after which the 10 rail 2 is set so that the end of the recess 5 will receive the end of the dove-tail 4, and the rail 2 is then moved longitudinally toward the rail 1, sliding upon the dove-tail 15 projection 4 which connects the rail 2 to the coupling member 3 for preventing either lateral or vertical movement of the rail 2 with respect to the coupling. Lateral or 20 vertical movement of the rail 1 with respect to the coupling is prevented by the dove-tail extension 9 and the elliptical projection 10, which are seated in the openings 7 and 8 respectively of the extension 6. After the 25 rail 2 has been pushed until its angled end engages the shoulder 12, the bolt 15 is inserted through the opening 14 and held therein by the usual form of nut, which securely connects the meeting ends of the rails 1 and 2, to prevent spreading of the rails 30 and to allow for a limited longitudinal movement of the rails under expansion and contraction.

What is claimed is:—

1. In a rail joint, a track rail having a 35 laterally disposed extension formed upon one end thereof, said extension being provided with a dove-tailed recess communicating with its inner surface and extending downwardly through the extension at an incline to the vertical, a coupling member having a dove-tail projection formed thereupon for seating in said dove-tailed recess, a longitudinally extending dove-tailed extension formed upon the opposite side of said 40 coupling member from said first named dove-tailed extension, and a complementary track rail having a longitudinally extending dove-tailed recess formed in its inner surface for receiving the dove-tailed projection formed upon said coupling member, the meeting ends of said track rails being cut at an incline to the vertical and substantially parallel to said inclined dove-tail recess and projection. 50

2. In a rail joint, a track rail having a laterally disposed extension formed upon one end thereof, said extension being provided with a dove-tailed recess communicating with its inner surface and extending 60 downwardly through the extension at an incline to the vertical, a coupling member having a dove-tail projection formed thereupon for seating in said dove-tailed recess, a longitudinally extending dove-tailed extension 65 formed upon the opposite side of said cou-

pling member from said first named dove-tailed extension, and a complementary track rail having a longitudinally extending dove-tailed recess formed in its inner surface for receiving the dove-tailed projection formed 70 upon said coupling member, the meeting ends of said track rails being cut at an incline to the vertical and substantially parallel to said inclined dove-tail recess and projection, and an elongated opening 75 extending horizontally and transversely through said extension, said coupling member and said last named complementary rail, and a bolt extending through said opening for connecting said members. 80

3. In a rail joint, a track rail having a laterally disposed extension formed integrally therewith and projecting longitudinally from one end of the rail, a dove-tailed recess formed in the inner face of said extension and extending downwardly at an oblique incline to the vertical, said extension provided with a substantially elliptical recess formed in its outer surface outwardly of the dove-tailed recess and extending downwardly substantially parallel with the dove-tailed recess, a coupling member, a dove-tailed projection, and an elliptical projection formed upon said coupling member and seated in said dove-tailed and elliptical recesses, said coupling member provided with a longitudinally extending dove-tailed projection formed upon its face opposite to said first named dove-tail projection, and positioned substantially equidistant of its 100 upper and lower surfaces, a complementary rail provided with a dove-tailed recess formed in its inner surface and adapted to receive the dove-tailed projection formed upon said coupling member, said inclined dove-tailed recess and said inclined elliptical recess having their walls slightly converging as they extend downwardly, the meeting ends of said rails and the end of said coupling member which engages a portion of said extension being cut at an incline substantially parallel to said first named dove-tailed and elliptical recesses. 110

4. In a rail joint, a track rail having a laterally disposed extension formed integrally therewith and projecting longitudinally from one end of the rail, a dove-tailed recess formed in the inner face of said extension and extending downwardly at an oblique incline to the vertical, said extension provided with a substantially elliptical recess formed in its outer surface outwardly of the dove-tailed recess and extending downwardly substantially parallel with the dove-tailed recess, a coupling member, a dove-tailed projection, an elliptical projection formed upon said coupling member and seated in said dove-tailed and elliptical recesses, said coupling member provided with a longitudinally extending dove-tailed pro- 120 125 130

jection formed upon its face opposite to said first named dove-tail projection, and positioned substantially equidistant of its upper and lower surfaces, a complementary rail 5 provided with a dove-tailed recess formed in its inner surface and adapted to receive the dove-tailed projection formed upon said coupling member, said inclined dove-tailed recess and said inclined elliptical recess having 10 their walls slightly converging as they extend downwardly, the meeting ends of said rails and the end of said coupling member which engages a portion of said exten-

sion being cut at an incline substantially parallel to said first named dove-tailed and 15 elliptical recesses, said extension, said coupling and said complementary rail provided with alining elongated openings extending horizontally and transversely therethrough and a bolt extending through said openings. 20

In testimony whereof I affix my signature in presence of two witnesses.
